HIS ATTORNEY.

UNITED STATES PATENT OFFICE

FRED M. SLATER, OF EASTON, PENNSYLVANIA, ASSIGNOR TO INGERSOLL-RAND COMPANY, OF JERSEY CITY, NEW JERSEY, A CORPORATION OF NEW JERSEY

PNEUMATIC TOOL

Application filed December 4, 1929. Serial No. 411,494.

This invention relates to pneumatic tools, but more particularly to the throttle valve actuating means of fluid actuated percussive tools of the hand held type.

5 The objects of the invention are to enable a pneumatic tool which is adapted to be normally gripped at its rearward end with only one hand, to be equipped with a pair of laterally extending grip members and to enable 10 the same throttle valve actuating lever to be used as a medium for manipulating the throttle valve when the tool is equipped with either a single grip member or with a plurality of grip members.

15 Other objects will be in part obvious and in part pointed out hereinafter.

The figure in the drawing is a sectional elevation of so much of a pneumatic tool as will serve to illustrate the invention.

20 Referring more particularly to the drawing, A designates a cylinder having a piston chamber B to accommodate a reciprocating hammer piston C.

A closure is provided for the rear end of 25 the piston chamber B in the form of a plate D which forms one side of a valve chamber E in the rear end of the cylinder A.

The plate D is provided with a rear inlet 30 passage F through which pressure fluid flows from the valve chamber E into the rearward end of the piston chamber B. Diametrically opposite from the inlet passage F and in the plate D is a front inlet passage G which may lead through the cylinder A to 35 the front end of the piston chamber B.

Within the valve chamber E is a distributing valve H of the oscillatory plate type to control the inlet passages F and G. The plate D forms a seat for the valve H and seated 40 on the rearward end of the cylinder A is a back head J, the forward end of which extends into the cylinder A and forms the rearward bounding surface of the valve chamber E.

45 The back head J may be of a conventional type and may be secured to the cylinder A in any suitable manner, as for instance, by side rods or bolts (not shown). The back head has an integral grip portion K which is spaced from the back head J by legs L and

O disposed diametrically opposite each other on the back head J to leave a space P therebetween of sufficient width to accommodate the operator's hand.

The grip member K as illustrated is only 55 of sufficient width to be grasped by one hand. When the tool is thus equipped it is customary for the operator to support a portion of the weight of the tool as well as to guide it by grasping the cylinder A with 60 the other hand.

Within the back head J is a recess Q having a threaded portion R to receive a hollow plug S to which may be suitably connected a conduit T for conveying pressure fluid 65 from a source of supply to the recess Q. Leading from the innermost end of the recess Q to the valve chamber E is a supply passage U through which pressure fluid may be supplied to the valve chamber E. 70

At the juncture of the recess Q and the supply passage U is a valve seat V for a throttle valve W in the form of a ball which controls communication between the recess Q and the passage U. 75

The means whereby the throttle valve W may be unseated may be of a conventional type, as for instance, a throttle lever X which may be pivoted to the leg L as by means of a pin Y and is adapted to bear 80 against a push rod Z disposed slidably in the back head to bear against the throttle valve W.

The throttle lever X is in the form of a bell crank comprising an arm b which bears 85 against the rod Z and a lever portion c which lies beneath the grip portion K and extends generally longitudinally thereof. Due to this arrangement the throttle lever X may be readily manipulated to unseat the 90 throttle valve W by the same hand whereby the grip portion K is grasped.

The tool so far described is more particularly adapted for horizontal drilling or in such positions where the weight of the 95 tool may not be conveniently supported by grasping only the rearward end thereof. There are times however when it is desirable to use a tool of this type for down-hole drilling, and when so used there is of 100

course no occasion for the operator to support the weight of the tool since then it may bear directly against the working implement intended to be actuated. To the end 5 that the tool may be readily adapted for use for down-hole drilling, in which case it is customary to guide it and hold it to the work from only the rearward end thereof, the said tool may be equipped with a plurality of grip members, as for instance, *d* and *e* which lie in the same longitudinal plane as the grip portion *K*.

In order to enable the grip members *d* and *e* to be secured to the grip portion *K* 15 the said grip portion *K* is provided with a bore *f* which extends longitudinally therethrough for the reception of a bolt *g* whereon the grip members *d* and *e* are disposed.

The ends of the bolt *g* may be threaded 20 to receive nuts *h* whereby the bolt *g* may be held in the correct assembled position and the grip members *d* and *e* may be clamped securely to the grip portion *K*.

As will be readily apparent, when using 25 the tool for down-hole work and in which case the tool will be equipped with the grip members *d* and *e*, it would be extremely inconvenient for the operator to manipulate the throttle valve *W* by means of the throttle lever *X*. In order to enable the throttle valve *W* to be unseated without necessitating the releasing of one of the grip members *d* and *e*, an actuating lever *j* is mounted pivotally on the bolt *g* as by means of a pin 30 *k*, and said actuating lever has a lever portion *o* which extends generally longitudinally of the grip member *d* so that it may be readily grasped by the same hand whereby the grip member *d* is gripped. The actuating lever *j* has a laterally extending arm *p* which extends into a slot *q* in the bolt *g* and through which the pin *k* extends.

The actuating lever *j* is so located that that portion thereof through which the pin 45 *k* extends overlies the throttle lever *X* and has a projection *r* which extends laterally of the lever portion *o* and engages a notch *s* in the throttle lever *X*. In this way the throttle lever *X* and the actuating lever *j* will be interlocked with each other so that when using the tool for down-hole drilling the throttle valve *W* may be readily unseated by merely manipulating the actuating lever *j*. The movement of the actuating lever *j* will then be transmitted through the throttle lever *X* to the rod *Z* which will unseat the throttle valve *W*.

From the foregoing, it will be apparent 60 that for drilling in positions in which it becomes necessary for the operator to support the entire weight of the tool, the grip members *d* and *e* and the bolt *g* whereby the members are secured to the grip portion *K* may be removed from the tool and the 65 tool may then be grasped on the cylinder

with one hand and with the other hand on the grip portion *K*. When thus using the tool the throttle valve *W* may be actuated by means of the throttle lever *X*.

When using the tool for down-hole drilling the grip members *d* and *e* may be attached to the grip portion *K* and the actuating lever *j* may be pivoted to the bolt *g* so that the projection *r* will be inserted in the notch *s*. The tool will then be adapted 70 for use in down-hole drilling and in which case the throttle valve *W* may be unseated by means of the actuating lever *j* through the medium of the throttle valve *W*.

As has been before stated, the grip members *d* and *e*, together with the throttle lever *j*, may be attached or detached in accordance with the exigencies of the work. Although where this slight additional weight 80 of the grip members and their securing means is not objectionable, said grip members may remain permanently attached to the grip portion *K*.

I claim:

1. In a pneumatic tool, the combination 85 of a cylinder and a back head having a handle whereby the tool may be held to the work, a throttle valve in the back head, a throttle lever pivoted on the handle and movable by manual pressure applied directly thereto to actuate the throttle valve when the tool is being held by the handle, a pair of grip members forming an alternative means of holding the tool, means for securing the grip members to the handle, and an actuating lever adjacent one grip member and engaging the throttle lever for transmitting the movement of the actuating lever through the throttle lever to the throttle valve, said actuating lever being movable by manual pressure applied directly thereto when the tool is being held 90 by the grip members.

2. In a pneumatic tool, the combination 95 of a cylinder and a back head having a handle whereby the tool may be held to the work, a throttle valve in the back head, a throttle lever pivoted on the handle and movable by manual pressure applied directly thereto to actuate the throttle valve when the tool is being held by the handle, a pair of grip members forming an alternative means of holding the tool, a bolt for securing the grip members to the handle, and an actuating lever pivoted on the bolt adjacent one grip member and interlockingly engaging the throttle lever for transmitting the movement of the actuating lever through the throttle lever to the throttle valve, said actuating lever being movable by manual pressure applied directly thereto when the tool is being held by the grip members.

3. In a pneumatic tool, the combination 100 of a cylinder and a back head having a handle whereby the tool may be held to the

work, a throttle valve in the back head, a throttle lever pivoted on the handle and movable by manual pressure applied directly thereto to actuate the throttle valve when the tool is being held by the handle, said 5 throttle lever having a notch therein, a pair of grip members forming an alternative means of holding the tool, a bolt for securing the grip members to the handle, an actuating lever pivoted on the bolt and extending longitudinally of one grip member, and a projection on the actuating lever engaged by the notch whereby the throttle lever may be actuated by the actuating lever for opening 10 the throttle valve, said actuating lever being movable by manual pressure applied directly thereto when the tool is being held by the grip members.

4. In a pneumatic tool, the combination 20 of a cylinder and a back head having a handle, a throttle valve in the back head, a throttle lever pivoted on the handle to actuate the throttle valve, a pair of grip members extending laterally from the handle, 25 means for securing the grip members to the handle, said means and the grip members being detachable therefrom, and an actuating lever adjacent one grip member and detachable therewith and engaging the 30 throttle lever for transmitting the movement of the actuating lever through the throttle lever to the throttle valve.

5. In a pneumatic tool, the combination 35 of a cylinder and a back head having a handle whereby the tool may be held to the work, a throttle valve in the back head, a throttle lever pivoted on the handle and movable by manual pressure applied directly thereto to actuate the throttle valve when the tool is being held by the handle, a pair 40 of grip members extending laterally from the handle and forming an alternative means of holding the tool, means for securing the grip members to the handle, said 45 means and the grip members being detachable therefrom, and an actuating lever adjacent one grip member and detachable therewith, said actuating lever engaging the throttle lever for transmitting the 50 movement of the actuating lever through the throttle lever to the throttle valve, said actuating lever being movable by manual pressure applied directly thereto when the tool is being held by the grip members.

55 In testimony whereof I have signed this specification.

FRED M. SLATER.
